PLATE OR SIMILAR ARTICLE

Tsuneo Murase, 15015 Gramercy Place, Apt. 3-C,
Gardena, Calif.

Filed Jan. 31, 1964, Ser. No. 78,458

Term of patent 3½ years

(Cl. D44—15)

The figure is a plan view of a plate or similar article, showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
